CHILD'S TOOTHBRUSH HOLDER

Earl E. Varner and Adam C. Zilem, Waco, Tex.
Application April 15, 1957, Serial No. 45,739

Term of patent 14 years

(Cl. D4—3)

Fig. 1 is a perspective view of a child's toothbrush holder, showing our new design.

Fig. 2 is a rear elevational view thereof; and
Fig. 3 is a top plan view thereof.

The undisclosed side of the toothbrush holder is substantially like the side shown.

We claim:

The ornamental design for a child's toothbrush holder, substantially as shown and described.
